(57) **CLAIM**

The ornamental design for a self-adjusting furniture foot assembly, as shown and described.

DESCRIPTION

FIG. 1 is a front perspective view of a self-adjusting furniture foot assembly showing my new design; FIG. 2 is a top plan view thereof;

FIG. 3 is a side elevational view thereof; and, FIG. 4 is a bottom plan view thereof.

The broken lines in the Figures are for illustrative purposes only and form no part of the claimed design.
